UNITED STATES PATENT OFFICE

2,531,131

BUCKET HOLDER

Axel E. F. Johnson, Lombard, Ill., assignor to
American Hospital Supply Corporation, Evans-
ton, Ill., a corporation of Illinois

Application October 30, 1948, Serial No. 57,472

3 Claims. (Cl. 248—129)

1

This invention relates to a bucket holder. The invention is particularly useful in connection with a roller equipped bucket holder sometimes known as a "kick bucket" and which may be moved about a floor which is being scrubbed, etc.

An object of the invention is to provide a bucket holder of sturdy structure in which a bucket may freely be placed, the weight of the bucket serving to bring about a tight connection between the bucket and the holder. Yet another object is to provide a bucket holder in which the bucket is automatically gripped when placed in the holder, the holder automatically releasing its grip upon the bucket when the bucket is merely lifted from the holder. A further object is to provide a holder structure which is self-centering for the bucket. A still further object is to provide a roller-equipped and bumper-equipped bucket holder of sturdy structure in which pivotally mounted levers are provided with inclined spring members for receiving buckets of various sizes and for automatically gripping the buckets when placed between said levers, means being provided for urging said levers to open position for releasing said bucket, when the bucket is lifted away from said holder. Other specific objects and advantages will appear as the specification proceeds.

The invention is shown in an illustrative embodiment by the accompanying drawing, in which—

Fig. 1 is a perspective view of a bucket holder embodying my invention, a bucket being supported by the holder; Fig. 2, a top plan view; and Fig. 3, a transverse sectional view, the section being taken as indicated at line 3—3 of Fig. 2.

In the illustration given, 10 designates a perimeter frame which is illustrated as of a circular shape. The frame 10 is formed of an angle bar, as shown best in Fig. 3. Secured to the vertical flange of the angle bar frame 10 is a bumper ring 11 formed of rubber or other suitable resilient material.

To the inner walls of the vertical flange of frame 10 are welded the web members 12 which provide a central socket adapted to receive the roller caster pin 13.

To the underside of the horizontal flange of the angle frame 10 is welded or otherwise secured a plurality of hinge leaves 14. The outer leaf 15 of each hinge is secured by welding or other means to one of several bars 16. The hinge leaves 14 and 15 are connected by the usual hinge pin 17.

Any number of levers or bars 16 may be employed. In the specific illustration given, three of the bars are hingedly connected along an in-

2

termediate point to the frame 10 and are spaced apart by substantially equal distances. The lower end of each bar 16 is provided with an inwardly extending flange 18. The inner end of each flange 18 is equipped with a resilient button 19 of rubber or other suitable material and similarly the top portion of each bar is shown equipped with a resilient button 20.

I bridge the angle of each of the bars 16 by 10 an inclined spring member 21 which preferably has end flanges welded to the vertical and horizontal portions of the bar 16. By inclining the spring member 21 inwardly, as illustrated, the bucket bottom is effective in springing the bottom 15 portion of the bar 16 outwardly and the upper portion of the bar 16 inwardly so that the bucket is tightly gripped by the bars. Also, the inclined strips 21 are effective in causing the bars to grip a great variety of buckets of differing sizes.

20 I provide means for normally urging the upper ends of the bar 16 outwardly so that a bucket may be freely placed within the holder and between the bars 16. In the specific illustration given, the vertical flange of frame 10 is equipped with an inwardly extending pin 22 and the bar 16 is equipped with an outwardly extending pin 23. A compression spring 24 is supported by the pins 22 and 23 and normally urges the lower portion of each bar 16 inwardly and thus causes 30 the upper portion of each bar to swing outwardly.

Operation

In the operation of the device, a bucket which is indicated by the numeral 25 may be placed 35 upon the holder and between the bars 16. The inclined members 21 engage the bucket sides and cause the lower portion of each bar 16 to swing outwardly while the upper portion of each bar 16 swings inwardly and tightly grips the bucket. 40 Thus the bucket is held by the inclined strips 21 and the upper portions of the spaced bars 16. In some instances, depending upon the size of the bucket, the bucket may rest upon the horizontal flanges 18, the upper portions of the bucket being engaged by the button equipped ends of the bars 16.

When it is desired to remove the bucket from the holder, it is only necessary for one to lift the bucket. The lifting of the bucket immediately releases the hinged levers or bars 16 and the spring 24 causes the upper portions of the levers 50 16 to swing outwardly, thus releasing the bucket.

While in the foregoing specification, I have set forth certain structures in considerable detail for the purpose of illustrating an embodiment of the

invention, it will be understood that such details of structure may be varied widely by those skilled in the art without departing from the spirit of my invention.

I claim:

1. In a bucket holder, a circular frame equipped with rollers, angle bars pivotally connected along their vertical portions to the frame, inclined spring members connecting the angularly extending portions of each lever, and a spring urging the bottom portion of each lever inwardly to cause the upper portion of each lever to move outwardly. 10

2. In a bucket holder, a circular angle bar, frame formed of a plurality of angle levers secured thereto at intermediate points along the levers by means of hinges, each hinge having one leaf secured to the underside of the horizontal flange of the frame and having another leaf secured to the lever near the lower portion thereof, each of the angle levers having its top and bottom portion connected by inclined straps, and a compression spring supported between the vertical flange portion of the circular frame and a portion of the lever below its pivot. 15 20

5 3. In a bucket holder, a circular frame equipped with rollers, angle bars pivotally connected along their vertical portions to the frame, inclined bucket-gripping members connecting the angularly-extending portions of each lever, and means urging the bottom portion of each lever inwardly to cause the upper portion of each lever to move outwardly.

AXEL E. F. JOHNSON.
